UNITED STATES PATENT OFFICE

147,650

DESIGN FOR A TOOTHBRUSH CABINET

Mowry John Hanni, Painesville, Ohio

Application July 3, 1946, Serial No. 131,317

Term of patent 14 years

(Cl. D4—3)

To all whom it may concern:

Be it known that I, Mowry J. Hanni, a citizen of the United States, residing at Painesville, in the county of Lake and State of Ohio, have invented a new, original, and ornamental Design for a Toothbrush Cabinet, of which the following is a specification, reference being had to the accompanying drawing, forming a part thereof.

The figure is a perspective view of a toothbrush cabinet, showing my new design.

The back of the toothbrush cabinet is substantially plain.

I claim:

The ornamental design for a toothbrush cabinet, as shown and described.

MOWRY JOHN HANNI.
